UNITED STATES PATENT OFFICE.

FRED V. HART, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MEANS FOR FEEDING ARTICLES IN STACKED RELATION.

1,352,744.

Specification of Letters Patent. Patented Sept. 14, 1920.

Application filed October 16, 1916. Serial No. 125,952.

To all whom it may concern:

Be it known that I, FRED V. HART, a citizen of the United States, residing at Lynn, in the county of Essex and State of Massachusetts, have invented certain new and useful Improvements in Means for Feeding Articles in Stacked Relation; and I do hereby declare the following to be a full, clear, and exact description of the invention, such 10 as will enable others skilled in the art to which it appertains to make and use the same.

This invention relates to a mechanism for feeding articles successively from a stack. 15 The invention is particularly adapted for use in feeding pieces of material which are wedge-shaped or tapering in one of their dimensions, so that they are not uniform in thickness. In feeding uniform articles or 20 pieces of material, it is common to arrange such pieces in a stack and to discharge them successively from the end of the stack. This mode of operation is easily carried out where each piece is of uniform thickness 25 from one extremity to another, so that the pieces will stack in parallel positions when lying one against another. Where the article to be fed is not of uniform thickness, but is tapered or wedge-shaped in one di- 30 mension, such articles will not stack prop- 35 erly if lying loosely one against another and in similar positions. This fact prevents the feeding of such articles from a stack by means of the mechanisms which are ordi- 40 narily used for that purpose.

The object of the present invention is to provide a mechanism by which articles tapering or wedge-shaped or otherwise irregular in one dimension may be stacked in 45 proper relation to each other, and may be delivered successively from the end of the stack and all in the same position.

To the foregoing end it is proposed, in accordance with the present invention, to 50 employ a construction or arrangement of parts such that, while the articles which are to be fed are, or may be in direct contact with each other at their thicker extremities, and may, in so far as such extremities 55 are concerned, be supported or controlled

as a unit, the thinner extremities of the articles are supported and controlled independently of each other, being so spaced apart as to preserve a general parallel relation of the articles in the stack, instead 55 of the fan-like arrangement which the articles tend to assume if lying upon each other at their thinner extremities.

In an application for Letters Patent of the United States filed May 22, 1916, Serial 60 No. 99,259 (renewal Ser. No. 202,643) by the present inventor, a feed-mechanism is disclosed which is adapted to operate in accordance with the present invention, but in the form specifically disclosed, the said 65 mechanism is adapted only for feeding articles from the lower end of a stack and the remaining articles in the stack are advanced by the action of gravity. A specific object of the present invention is to produce a 70 mechanism by which the method herein disclosed may be practised wherever it is necessary to feed articles from a stack in which the articles must advance in any direction in which the effect of gravity cannot be utilized for the purpose. 75

For the purpose just described, it is proposed to employ members or projections arranged in a series, spaced in accordance with the thickness of the thicker extremities of 80 the articles to be fed, these members being introduced between the thinner extremities of the articles. The thicker extremities of the articles, being in engagement with each other, may be advanced by any ordinary or 85 suitable means, such as a follower, while the thinner extremities are advanced by simultaneous movement of the members by which they are separated, and the entire stack may thus be advanced progressively, as the articles are withdrawn one by one from the end of the stack, while at the same time all of the articles are retained in their proper 90 stacked relation.

The foregoing and other objects and features of the invention are set forth more fully in the following description of the illustrated embodiment of the invention.

In the accompanying drawings Figure 1 is a side-elevation, partly in vertical-section, 100

of feed-mechanism embodying the present invention.

Fig. 2 is a plan-view, partially in section of the feed-mechanism with certain parts removed,

Fig. 3 is a detail-view, on a larger scale than the preceding figures, showing parts of the mechanism in a different operative position from that shown in Fig. 1, and

Fig. 4 is a vertical section on the lines 4—4 in Fig. 3, looking from right to left in the latter figure.

The invention is illustrated as embodied in a feed-mechanism adapted particularly to operate on either wedge-shaped heel-lifts or the strips of material from which said lifts may be cut. The pieces B of material are shown as having thicker edges 6 and thinner edges 8, and the pieces are placed and held in stacked relation with their thicker edges in engagement with each other. The means for separating and for advancing the thinner edges 8 of the pieces are in the form of two racks 10 and 12. The rack 10, which may be described as the "feed-rack," is double in form, having two parallel members, and the rack 12, which may be described as the "retainer-rack," is located between the two members of the feed-rack. The two racks are arranged to move within a recessed base-member 14, which has side-walls 16 which embrace the racks laterally and guide them in their longitudinal and vertical movements. The side-walls 16 may also contribute to the support of the pieces B, by engagement with their thinner lower edges 8 as shown in Fig. 4.

The teeth of the two racks are spaced apart by a distance equal to the thickness of the edges on extremities 6 of the pieces B, and they enter between the thinner edges 8, thus separating these edges so that the pieces may be held in stacked relation with their central planes in parallelism as shown in Figs. 1 and 3. The edges 8 are advanced, in feeding the stack, by the action of the feed-rack 10, which for this purpose is reciprocated longitudinally. As a convenient means for producing this movement of the feed-rack, it is shown as having a rearwardly-projecting extremity 18 pivotally connected with a crank-arm 20, that is fixed on a vertical rock-shaft 22. This rock-shaft is provided with an arm 24 carrying a roller 26 which engages a cam 28. The cam is mounted on a shaft 30, which is rotated by any suitable means, such as a pulley 32, by which it may be connected with a source of power.

The feed-rack is supported, from beneath, by a spring 34 inclosed within the base-member 14, and in order to permit vertical movement of the rack, it is connected with the crank-arm 20 by an elongated crank-pin

36 which projects loosely through a hole in the member 18.

At each rearward reciprocation of the feed-rack, the spring 34 yields so as to permit the rack to be depressed as the rack-teeth ride beneath the lower edges of the pieces B, and the amplitude of the longitudinal movement of the rack is such as to cause each tooth to move into engagement with the piece next in the rear of that which it previously engaged. The feed-rack is next advanced by the cam-mechanism with the result that the lower edges 8 of all of the pieces B are advanced through a space equal to the thickness of one of the thicker edges 6.

The retainer-rack 12 also is supported yieldingly by the spring 34, by reason of which it serves to urge the pieces upwardly into clamping engagement with an upper guide member 56 whereby said pieces are held and maintained in stacked relation with their thick ends in engagement. Longitudinal movement of this rack is prevented by engagement of its rear extremity with a stud 38 which projects upwardly from the base-member 14 and projects loosely through a hole in the retainer-rack, so as not to interfere with vertical movement of the rack. The retainer-rack 12 operates not only to confine the pieces in stacked relation but also to prevent the lower edges of the pieces B from following the rearward movement of the feed-rack 10. During such movement, the teeth of the retainer-rack remain in engagement with the edges 8, but during the advance or feeding movement of the feed-rack, the edges 8 ride over the teeth of the retainer-rack, which is thereby depressed, and at the end of the feeding-movement each tooth of the retainer-rack engages the piece next in the rear of that which it previously engaged.

The thicker edges 6 of the pieces are supported by engagement with the upper guide 56 and are advanced by means of a follower 40, which engages the rearmost piece in the stack. This follower slides upon the base-member 14 and it is provided with a tooth 42 which projects downwardly into engagement with the teeth of the racks. The follower is accordingly fed forward by the racks in the same manner and at the same rate as the lower edges of the pieces B.

At the forward or delivery-end of the stack, the foremost piece B is supported and definitely located in position to be discharged by spring-arms 44 projecting downwardly from the guide member 56, which constitutes the upper wall of the stack-holder. This foremost piece may be removed from the stack in any convenient manner, but for illustrative purposes, a mechanism has been shown which comprises

an endless chain 46 which is supported, at the top by a sprocket-wheel 48 fixed on a shaft 50. The chain 46 carries feed-fingers 52 arranged at suitable intervals, these fingers having hook-like extremities which are adapted to pass downwardly between the spring-arms 44 so as to engage the upper edge of the foremost piece B and slide it downwardly, out of the stack-holder, as shown in Fig. 1. The piece so removed from the stack may then be conducted in any convenient manner to the instrumentalities of the machine in which the piece B is to be utilized.

15 The shaft 50 is shown diagrammatically as connected with, and driven from, the shaft 30, by means of a sprocket chain 54, so that the shafts 30 and 50, and the parts actuated thereby, may operate in suitably 20 timed relation.

The feed-mechanism above described is suitable for comparatively short pieces of material such as heel-lifts. It is equally adaptable, however, to the operation of feeding elongated pieces or strips, and it may be understood that for this purpose it is necessary only to provide a plurality of sets of racks arranged in parallel relation, together with a plurality of mechanisms for withdrawing the strips from the stacks. The several rack-mechanisms may be driven from a single cam-mechanism, such as that illustrated, and for the purpose of connecting them for such common actuation, the shaft 35 22 may be provided with a crank-arm 58, to which is pivoted a transverse rod 60 by which the other rack-mechanisms (not shown) may be actuated.

The mechanism herein described is positive in its action, so that it will operate reliably, notwithstanding such slight variations in the form and dimensions of the pieces B as may be expected to occur in practice. While the invention has been described 45 as employed in connection with pieces of material which are wedge-shaped in cross-section, it will be understood that in its broader aspects, it is applicable generally to the feeding of articles which are approximately uniform in shape, but each of which has a comparatively thick extremity and a comparatively thin extremity, so that it is not capable of being stacked in the ordinary manner like articles having extremities of 50 55 equal thickness.

The nature and scope of the invention having been indicated and its preferred embodiment specifically described, what is claimed as new, is:

60 1. Mechanism for feeding uniformly tapering articles, having in combination, means for supporting the articles in a stack with their thicker extremities together; means for engaging and positively discharg-

ing articles successively from the end of the 65 stack; and means for advancing the thinner extremities of the remaining articles individually and positively.

2. Mechanism for feeding tapering articles, having, in combination, means engaging opposite extremities of said articles for holding and maintaining a stack of such articles with their thicker extremities together; means for withdrawing articles successively from the end of the stack; means 70 75 for controlling the advancing movement of the thicker extremities of the remaining articles as a unit, and means for controlling the advance of the thinner extremities of the remaining articles individually. 80

3. Feed-mechanism, having, in combination, substantially parallel guides acting upon opposite edges of a series of tapering articles stacked with their thicker portions together for maintaining said articles in such relation 85 one of said guides being smooth and engaging the thicker portions of said articles, and the other guide being provided with a series of projections adapted to enter between the thinner portions of the articles to space them 90 apart; and means for advancing all of said projections, intermittently, through a space equal to the thickness of the thicker portions of the articles, so as to advance all 95 of the thinner portions and permit the discharge of an article from the stack.

4. Feed-mechanism, having, in combination, means for holding a series of tapering articles in a stack with their thicker portions together and confining them against 100 displacement; means for advancing the thicker portions by engagement with the end of the stack; and means for separating the thinner portions and for advancing them by individual engagement therewith. 105

5. Feed-mechanism, having, in combination, means for clamping a series of tapering articles in a stack, with their thicker portions together; a follower engaging the end of the stack and movable to advance 110 the stack; and a series of members interposed between the thinner portions of the articles, to space them apart, said members being movable with the articles in the direction of advancement of the stack. 115

6. Feed-mechanism, having, in combination, means for clamping a series of tapering articles in a stack, with their thicker portions together; means interposed between the thinner portions of the articles to space 120 them apart; and means for advancing the stack as a whole.

7. Feed-mechanism, having, in combination, clamping means for confining a series of tapering articles in a stack, with their thicker portions together; means interposed between the thinner portions of the articles to space them apart; and means for with-

drawing articles singly from the end of the stack.

8. Feed-mechanism for operating on a series of tapering articles stacked with their thicker portions together comprising means acting on opposite ends of the stack for pressing the thicker portions of the articles together; means interposed between the thinner portions of the articles, to hold said portions apart; and means for withdrawing articles from the end of the stack.

9. Feed-mechanism for operating on a series of tapering articles in stacked relation with their thick ends in engagement, having, in combination, a rack extending longitudinally of the stack and provided with a series of teeth which enter between the adjacent thin ends of the articles so as to separate and retain the ends; and means for longitudinally reciprocating the rack to advance said thin ends intermittently.

10. Feed-mechanism, for operating on a series of tapering articles in stacked relation with their thick ends in engagement, having, in combination, two parallel racks with similarly inclined teeth extending longitudinally of the stack with said teeth interposed between adjacent thin ends of the articles; means for reciprocating one rack to advance said thin ends intermittently; and means for supporting the other rack movably so that its teeth may be withdrawn from between the thin ends of the articles during the advancing movement of the stack.

11. Feed-mechanism, for operating on a series of articles in stacked relation, having, in combination, a rack provided with teeth which enter between the edges of adjacent articles in the stack; means for reciprocating the rack to advance said edges simultaneously; and a follower for engaging and advancing the end of the stack, which follower also is in engagement with, and actuated by, the teeth of the rack.

12. Feed-mechanism, for operating on a series of tapering articles in stacked relation with their thick ends in engagement, having, in combination, a series of members adapted to be introduced between adjacent thin ends of the articles so as to space them apart; and mechanism for actuating said members in unison so as to move them both in the direction of feed of the stack and also transversely thereto, whereby each article is advanced in the direction of feed and is brought into engagement with said members in succession.

13. Mechanism for feeding uniformly tapering articles having, in combination, means for clamping a plurality of said articles in face-to-face stacked relation with their thin ends spaced apart, means for feeding said stack of articles, and means for ejecting said articles from one end of the stack.

14. Mechanism for feeding tapering articles having, in combination, clamping means for confining a plurality of said articles in stacked relation with their thick ends in engagement, and means acting collectively upon the thick ends of said articles and individually upon the thin ends thereof for feeding said articles through said clamping means.

15. Mechanism for feeding uniformly tapering articles having, in combination, means acting on opposite ends of said articles for confining a plurality of said articles in stacked relation, with their thick ends in engagement, means for spacing apart the thin ends thereof, means including said spacing means for feeding said articles, and means for ejecting said articles from one end of the stack.

16. Mechanism for feeding uniformly tapering articles having, in combination, means for holding a stack of said articles with their thick ends in engagement, a follower engaging one end of the stack, and reciprocating means engaging the thin ends of said articles and said follower for advancing said follower and said articles during each of its movements in one direction.

17. Mechanism for feeding uniformly tapering articles having, in combination, means for clamping a stack of said articles by engagement with their thick and thin ends, and means independent of said clamping means for advancing the stack of articles.

18. Mechanism for feeding uniformly tapering articles having, in combination, means for holding a plurality of said articles in stacked relation with the central plane of one article bearing a fixed relation to the central planes of the contiguous articles, including means for gripping said articles in the planes of the tapers, and separate means for advancing the stack of articles.

19. Mechanism for feeding tapering articles having, in combination, means for holding said articles in stacked relation with their thick ends in engagement and positively feeding both the thick ends and thin ends thereof, means for engaging the forward end of the stack to definitely locate the foremost article, and means for ejecting the articles so located from one end of the stack.

20. Mechanism for feeding uniformly tapering articles having, in combination, means for clamping a plurality of said articles in stacked face-to-face relation, means for positively feeding said articles while maintaining said relation and means for ejecting the successive articles from one end of the stack.

21. Feed mechanism having, in combination, means for holding a plurality of taper-

ing articles in stacked face-to-face parallel relation and confining said articles against displacement, and means for positively feeding said articles through said holding means 5 while maintaining said mutual relationship.

22. Feed mechanism having, in combination, means acting on the opposite ends of a plurality of similarly disposed tapering articles for holding them in stacked face-to-

face parallel relation with their thick ends in 10 engagement and their thin ends spaced apart and for confining them against displacement, and means for feeding the stack with respect to said holding means, said feeding means acting upon the thick ends of the articles 15 collectively and upon the thin ends thereof individually.

FRED V. HART.
